(57) **CLAIM**

The ornamental design for a display screen with a transitional graphical user interface as shown and described.

DESCRIPTION

FIG. 1 is a front view of a first image for a display screen with a transitional graphical user interface showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The outermost broken lines showing a display screen and remaining broken lines showing elements of the graphical user interface illustrate portions of the article and form no part of the claimed design. The stippled circles and hatch pattern filled circles within the graph of FIG. 5, as well as the diagonal hatch lines within the graphs of FIGS. 5 and 7 illustrate portions of the graphical user interface and form no part of the claimed design. The appearance of the graphical user interface sequentially transitions between the images shown in FIGS. 1-7. The process or period in which one image transitions to another image forms no part of the claimed design.

1 Claim, 7 Drawing Sheets
